UNITED STATES PATENT OFFICE.

RUDOLPH KOTKAS, OF PORTLAND, OREGON.

CIRCUIT CLOSER.

Application filed February 6, 1920. Serial No. 356,597.

To all whom it may concern:

Be it known that I, RUDOLPH KOTKAS, a citizen of United States, residing at Portland, in the county of Multnomah and State of Oregon, have invented certain new and useful Improvements in Circuit Closers, of which the following is a specification; reference being had therein to the accompanying drawings.

10 This invention relates to a circuit closing apparatus particularly adapted to be attached to the floor of a building, and has for its object the provision of means attached to the floor structure that will operate for closing a circuit and ringing a bell or sounding a signal when a person walks upon or over the floor.

Another object is the provision of a comparatively simple and efficient vibrating device that will intermittently close and open a circuit for sounding a signal by a person walking upon the floor of a building.

With these and other objects in view, my invention comprises certain other combinations, constructions and arrangements as will be hereinafter fully described, illustrated in the accompanying drawings, and more particularly pointed out in the appended claims.

30 In the drawings:

Figure 1 is a view in side elevation of an apparatus constructed in accordance with the present invention, shown attached to the floor structure of a building.

35 Figure 2 is a section taken on line 2-2, Fig. 1, and looking in the direction of the arrows.

Figure 3 is a section taken on line 3-3, Fig. 2, and looking in the direction of the arrows.

40 Figure 4 is a fragmentary perspective view of the apparatus, showing particularly the vibrating lever and its co-operating parts.

45 Referring to the drawings by numerals, 1 designates the main joist upon which are fastened the boards 2 constituting the floor of a building or dwelling. Vertical strips 3 are fastened to the main joist 1, the upper ends of the strips 3 resting against the floor. Secured to the strips 3, but slightly spaced at its end from the floor is a secondary joist 4. Vertical strip 5 and vertical strip 6 are secured to the outer face of the secondary joist 4, the strip 5 being short in length as

compared to strip 6. The strip 6 extends a considerable distance below the lower edge of joist 4 so as to pivotally support, at 7, the lever 8 of the tensioning device 9, hereinafter specifically described.

60 It is to be noted that, as the main joist 1 is not supported directly under my apparatus, weight upon boards 2, directly above the apparatus, will cause a slight depression or jar sufficient to actuate the delicately mounted levers of the apparatus.

Pivotedly mounted, at 10, upon the short strip 5 is a primary lever 11. Upon the inner end of the lever 11 is a bifurcated plate 12. An auxiliary lever 13 is pivotally mounted, at 14, upon the long strip 6; near its inner end is a pin 15 that is slidably mounted in the bifurcation of plate 12, so that when the primary lever 11 is swung upon its pivot 10 similar movement will be imparted to 75 the auxiliary lever 13.

An upwardly bowed arm (Fig. 3) 16 is fastened at its inner end to the bottom edge of lever 13, and the outer end of arm 16 is slightly above the upper edge of the lever 13; on the lever 13 is a fastening member or pin 17, and suspended upon the upper end of arm 16 and pin 17 is a taut string or like means 18; suspended upon the string 18 is a vibrating lever 19. A contact wire 20 extends through the lever 10 and on its ends are downwardly-extending fingers 21. Fastened to the side of auxiliary lever 13 is a bracket 22, and mounted upon the top of the bracket are terminal cups 23. In the terminal cups on bracket 22 is quicksilver, and the quicksilver in these cups is adapted to be engaged by the fingers 21 for closing a circuit through wires 24, 25 and 26 with the bell or signal 27.

90 The tensioning device 9 includes the pivotally mounted lever 8 which is connected at its outer end by link 28 with the primary lever 11; any movement of the lever 8 will swing the lever 11 upon its pivot 10, thereby imparting movement to the auxiliary lever 13, vibrating the vibratory lever 19 that is suspended upon the string 18, causing the contact wire 20 and its fingers to close a circuit through cups 23 and actuate 95 the signal 27. The bracket 29 is fastened to the main joist 1 near its lower edge, and a vertical set screw 30 is threaded through the bracket; the inner end of the set screw engages a bowed spring 31, which spring 31 105

is fastened at 32 to the under face or lower edge of lever 8. A coil spring 33 is fastened by eye 34 to the lever 8 near its outer end, and the opposite end of the coil spring 33 is fastened by eye 35 to bracket 29. By adjusting the set screw 30 upon the bracket 29 the adjustment of the levers can be obtained to a nicety, so that the vibrating lever is suspended in position for permitting the 10 contact wire 20 to close the circuit through the quicksilver-carrying cups 23 when the slightest vibration of the device is caused by a person walking upon the floor. The device is extremely sensitive, and, therefore, 15 the slightest step upon the floor will cause vibration of the vibratory lever 19, resulting in a signal or alarm being sounded. I have found that the foregoing statements, as well as the structure illustrated in the accompanying 20 drawing is absolutely correct by experimenting with a working model.

While I have described and illustrated the preferred embodiments of my invention, certain minor changes or alterations may be 25 found expedient in the manufacture of my apparatus on a large scale, and, therefore, I reserve the right to make such changes or alterations as shall appear to one skilled in the art to which this invention relates and

which fairly fall within the scope of the ap- 30 pended claims.

What I claim is:

1. In a device of the class described, the combination of a pair of levers pivotally connected, tensioning means for said levers 35 movably connected directly to one of the levers, the other lever provided with an arm and a bracket, a vibratory lever suspended upon the arm and the lever carrying said arm, whereby the vibratory lever is free to 40 swing in a vertical plane upon the first-mentioned levers being moved, terminals carried by said bracket, and said vibratory lever provided with means for engaging the terminals of the bracket and closing a cir- 45 cuit.

2. In a device of the class described, the combination of lever means provided with circuit-closing means actuated when the lever means is operated, a tensioning device 50 for said lever means comprising a lever, a bracket, a set screw for said lever, a spring interposed between the lever and the set screw, and a spring fastened to said lever and bracket.

In testimony whereof I hereunto affix my signature.

RUDOLPH KOTKAS.
